UNITED STATES PATENT OFFICE.

BRUCE BARTHOLOMEW, OF BERKELEY, CALIFORNIA.

GEOMETRICAL INSTRUMENT.

Application filed March 16, 1922. Serial No. 544,130.

To all whom it may concern:

Be it known that I, BRUCE BARTHOLOMEW, a citizen of the United States, residing at Berkeley, in the county of Alameda and State of California, have invented certain new and useful Improvements in Geometrical Instruments, of which the following is a specification.

My invention is a geometrical instrument combining dividers and parallel rulers, particularly useful for laying off points and ruling lines on metal work.

Referring to the annexed drawing in which my invention is illustrated and which forms a part of this specification:

The figure is a plan view of my instrument.

My geometrical instrument includes a plurality of divider and ruler bars 1, and a pair of pivot bars 2 and 3 inclined to said bars, which pivot bars are pivoted to the bars 1 by pivots 4 and 5 respectively, in such relation that the bars 1 are parallel to each other and the bars 2 and 3 are parallel to each other. The ends 6 of the bars 1 are pointed and in said ends of said bars are punch holes 7 respectively. One end of each of the pivot bars 2 and 3 is extended for a considerable distance beyond the outermost divider bar 1 in order that these extended ends may be grasped by the operator of the instrument. Thus the instrument may be readily manipulated. It will be noticed that these pivot bars lie relatively close together so that their corresponding extended ends readily form a hand grip.

In the present embodiment of my invention I have shown eight bars 1. When it is

desired to divide a surface into seven equally spaced divisions the points 6 of the bars 1, 40 2 and 3 are swung on their pivots until the two outermost bars 1 are placed on the surface at the outermost points of the distance to be divided, and the points 6 of the intermediate bars 1 will locate the intermediate 45 points. The points may be marked on the metal surface by scratching the surface with the points 6.

By swinging the bars 1, 2 and 3 on their pivots, the bars 1 may be spaced at different 50 distances apart and used as rulers for ruling off parallel lines at corresponding distances apart.

The points of rivets may be laid off on metal work by first locating said points with 55 the bars 1 and then punching the points on the work with a punch through the holes 7.

Having described my invention, I claim:

A geometrical instrument comprising a plurality of divider and ruler bars so arranged that they are constantly held in parallel relation, a pair of pivot bars pivoted to each of said divider bars and extending at an angle to the latter, said pivot bars being 60 so arranged that they will constantly be in parallel relation, said pivot bars also extending for a considerable distance beyond the outermost divider bars, each of said divider bars being pointed at one end and having a 65 hole at its sharpened end, said holes extending through each divider bar in a direction at right angles to the plane of said pivot bars.

In testimony whereof I affix my signature.

BRUCE BARTHOLOMEW.
